APPARATUS FOR UNIFORMLY DRAWING A PLURALITY OF FILAMENTS

George Allison Kinney, Glen Mills, Pa., assignor to E. I. du Pont de Nemours and Company, Wilmington, Del., a corporation of Delaware

Application June 30, 1954, Serial No. 440,501

6 Claims. (Cl. 18—8)

This invention is concerned with apparatus for drawing or stretching shaped articles, such as yarn, ribbons and the like at elevated temperatures, and more particularly with draw or snubbing pins, which can be held close to a desired temperature.

In the production of shaped articles, such as artificial yarn, it is common practice in the textile industry to stretch the yarn to increase its tenacity. U. S. Patent 2,289,232 discloses the use of a snubbing pin to localize the drawing stresses. Such pins are particularly desirable when drawing fibers prepared from linear condensation polymers, such as the polyamides, polyesters, polyethers, polyanhydrides and polyacetals such as described in U. S. Patent 2,071,251. In many cases it is necessary to heat the draw pin to obtain optimum yarn processing conditions.

In the manufacture of a product having a wide range of utility in the textile field, it is important that uniform physical properties be obtained. With reference to yarns of linear condensation polymers, it has been found that variations in the drawing process are reflected critically in certain yarn properties. Apparently this results from the fact that the crystallite orientation along the fiber axis, as shown by X-ray examination, is a function of the draw ratio of the yarn. For example, the affinity of these fibers for dye-stuffs decreases markedly with increasing orientation. In some cases, a change of about 3-4° C. in the temperature of the draw pin, other conditions remaining constant, will result in a perceptible difference in dyeability. For this reason it is very desirable to use a draw pin which will vary no more than about 1° C. from the selected operating temperature. Unfortunately, it is economically undesirable to employ the large number of control devices required to provide individual temperature controls for each pin.

The use of a manifold vapor heated draw pin system is desired for economy, but difficulties arise, such as in keeping the temperatures of the pins uniform because of uncontrollable accumulation of condensed liquid or of noncondensable gases within the hollow pins. The accumulation of condensed liquid cools the pin, while the stagnation of noncondensable gases accomplishes the same result by preventing an adequate supply of vapor from reaching the pin. The tendency of liquids and gases to accumulate in the pins is aggravated by the usual positioning of the pins inclined from the horizontal to minimize any tendency of the yarn to tangle at the pins; for convenience in string-up, the pins are preferably sloped downward.

An object of this invention is to provide apparatus having a plurality of vapor-heated, hollow draw pins readily controllable within close temperature limits at any desired temperature. More specifically, the invention has as an object the provision of a manifold unit in which both the condensed fluids and the noncondensable gases are removed efficiently from the draw pins and replaced by the condensable vapors of the heating medium. Another object is to provide such a unit which is quickly vented of noncondensable gases both at start-up and during operation without applying vacuum or removing the unit from

2

the site of operation. A further object is to provide a manifold draw pin apparatus which is simple, inexpensive to build and easy to maintain in operation. Additional objects are apparent hereafter.

5 The above objects are accomplished by the present invention which, briefly described, comprises a sealed manifold unit in which a plurality of hollow draw pins are integrally attached to a boiler. The hollowed-out portion of each draw pin is substantially conical in shape, providing for the continuous downward flow of condensed liquid back into the boiler and the continuous upward displacement of noncondensable gases into the upper section of the boiler. Accumulated noncondensable gases are easily vented by opening valves at the top of the boiler while the heating medium continues to boil. The apparatus of this invention thus serves to heat shaped articles, such as filaments, rods, tubing, ribbons and yarns which are traveling from one place to another and provides a way to localize heat and stress on these articles to permit uniform drawing.

10 20 The apparatus comprises a sealed unit, such as a boiler, containing heating media and means, and having a lateral outlet to which is attached, either directly or indirectly, a pin, usually cylindrical, which has an internal, hollow, tapered portion, the wide taper of which is at the end of the pin nearest the unit, the bottom taper sloping in a downward direction toward the bottom portion of the unit and the upper taper sloping in an upward direction toward the upper section of the unit. If the pin is connected to the unit or boiler through a third passageway, 25 30 35 the member containing that passageway is generally similarly tapered internally and the tapered edges are cooperatively aligned with those of the pin. Optionally, the entire apparatus or any portion of it may be baffled to promote the continuous flow of vapor through the draw pin and to isolate the noncondensable gases in the upper section of the boiler.

The invention will be more fully understood from the following description and the accompanying drawings, in which:

40 Figure 1 is a view in front elevation of a bank of draw pins, in which the view of the draw pin at the right is taken on A—A of Figure 2 and a portion of the entire front of the right side of the unit is cut away to show detail;

45 Figure 2 is a cross-sectional view taken on the line 2—2 of Figure 1;

Figure 3 shows a cross-sectional view of an alternative design of the unit; and

Figure 4 is a cross-sectional view taken on the line 50 4—4 of Figure 3.

As illustrated in Figures 1 and 2, one embodiment of this invention comprises an elongated cylindrical boiler 1 suitably enclosed by end plates 2. Openings 3, shown in Figure 2, are provided at intervals in the upper portion 55 of the boiler, and hollow substantially cylindrical members or blocks 4 are sealed to the boiler at each opening. The hollow channel 5, shown in Figure 2, in each block is tapered, the widest section corresponding in cross-section to the opening 3 in the boiler. Near the end of 60 the block a drilling 8 is made substantially at right angles to and meeting channel 5, and at this location, a hollow cylindrical draw pin 6 is mounted, preferably at right angles to the block and in a downward direction. The hollow portion 7 of the draw pin is also tapered, having substantially the shape of a cone or truncated cone, and is connected to the tapered channel 5 in the block by opening 8 in the side of the block. While the pin may be used in a horizontal position, the downward slope of the pin shown in Figure 1 assures that successive turns 65 70 of the yarn 9 wrapped about the draw pin will remain separated; preferably the draw pin is inclined at least

about 3° from the horizontal. The hollow portion 7 of the draw pin is tapered sufficiently to overcome the reverse tilt of the pin and provide a downward slope from the end of the pin towards the manifold of at least about 1° from the horizontal. Accordingly, vapor from the heating medium 10 in the boiler condenses in the draw pin and drains from the pin at the bottom 33 through opening 8 into channel 5 in the block and down the slope 34 of the block back into the boiler. At the same time, the continuous flow of vapor to the pin displaces non-condensable gases which may be present in the pin upwards from the pin being directed by surface 35, through the tapered channel in the block, being directed by surface 36, and into the upper section of the boiler for removal at vent 14.

With a boiler in the horizontal position, horizontal tubes 11 are provided to run the entire length of the boiler near the bottom of the vessel and open to the outside at each end. Suitable rod-shaped electrical heating elements 12 are utilized to provide uniform heating throughout the boiler. Preferably two heating elements are used, one of which is designed to operate continuously and provide about 60-85% of the heat required, while the other is operated by suitable controls to supply heat as required to maintain the unit at the desired temperature. A well 13 is provided at one end of the boiler in the upper part of the vessel for a temperature controller to be used in conjunction with the heating elements. Temperature controllers having the required sensitivity to maintain the unit within 1° C. of the desired temperature are commercially available and methods of their use are well-known in the art. The boiler need not be horizontal, for operation on an inclined plane or in the vertical is possible. Since the horizontal positioning provides for uniform heating of the blocks and pins with a minimum of control, the horizontal positioning is preferred.

At each end of the boiler a vent 14 is provided. By the use of suitable valves (not shown) the vents can be closed to seal the apparatus during operation or opened to vent the noncondensable gases. The vents, automatic or hand-operated are usually used to charge the vessel with heating fluid 10 which may be almost any liquid which has a sufficiently high vapor pressure at the operating temperature. "Freon 113" (trichlorotrifluoroethane) is very desirable because it causes little or no corrosion. "Freon 113" is also advantageous in that its heavy vapors aid the displacement of noncondensable gases (usually air) to the top of the boiler. The amount of heating fluid charged to the vessel is not critical; however, the liquid level should be high enough to cover the tubes containing the heating elements to avoid super-heating the vapor, but the level should not be so high that flooding of the draw pins occurs.

The apparatus may be constructed from steel or other common materials; however, it is preferred that the draw pins and temperature control well be fabricated of copper to obtain high sensitivity towards the transfer of heat. The unit should be sealed air-tight by usual techniques and covered with insulation, except for the draw pins or the active sections thereof, to obtain optimum results. Usually it will be desirable to cover the draw pins with thin sleeves of ceramic material to decrease abrasion of the pins by the yarn. "Alsimag," a bonded titanium dioxide, is excellent material for this purpose. Although the apparatus may vary in size, it will usually be designed to provide draw pins having diameters in the range of about 0.25 inch to about 2.5 inches. At high yarn speeds pins of even greater diameter may be used.

Operation of the unit is begun by charging the boiler with an excess of the liquid heating medium at regular atmospheric pressure, closing the valves at the vents and refluxing the heating medium at a temperature somewhat higher than the desired operating temperature.

The unit is then vented by quickly opening and closing the vents at each end of the vessel several times, leaving the unit substantially free of noncondensable gases. The unit may then be operated under close temperature control for long periods of time. In practice it is often found that a small quantity of noncondensable gas is adsorbed in the metallic walls of the vessel, so that an additional venting is sometimes desirable after operating the unit a few days. The ability to vent the apparatus in its operating position without the use of vacuum is an outstanding feature of the invention.

Example

A bank containing 6 draw pins was constructed in accordance with the preceding description, using 2.5" steel pipe for the boiler. The remainder of the unit was also constructed of steel with the exception of the draw pins and temperature control well which were made of copper. The apparatus was covered with a 2" layer of asbestos insulation except for the draw pins, which were covered with "Alsimag" sleeves. Two rod-type electrical heating elements and a temperature controller of the pressure bulb type equipped with a micro-switch were obtained from commercial sources; one heating element was set to operate full time and the other was set to operate at the demand of the temperature controller. The boiler was charged with "Freon 113"; this was heated to 135° C.; and the boiler was vented by quickly opening and closing the valves three times at each end in alternation. The temperature of the boiler was then dropped to about 99° C., and the temperature of the draw pins was measured with calibrated thermocouples and a reliable potentiometer. The temperature showed a slight cyclic change within the limits 99.5° C. maximum and 98.5° C. minimum, the maximum pin-to-pin difference at any time being 0.3° C. After 24 hours of continuous operation the temperature limits were 98.4° C.-99.5° C. with a maximum pin-to-pin difference of 0.35° C.

In the previously described embodiment of the invention the removal of the noncondensable gases from the pin depends on the constant flow of fresh vapor into the pin and the convenient escape path for the noncondensable gases through the tapered channel. While this design is effective, noncondensable gases can become mixed to some extent with condensable vapors through turbulence and therefore recirculate through the pin. This is not undesirable when the amount of noncondensable gas present in the vessel is low, which will be the normal case; as pointed out above, the unit may be vented occasionally to void the unit of noncondensable gases. However, when a large number of units are in use, it may happen that some units are not vented over a long period of time and that an appreciable concentration of noncondensables builds up in some manner. For example, it is known that when water is used as a heating medium there may be a slow reaction with metallic elements in the apparatus with the evolution of hydrogen. Units of the above design in which noncondensable gases have been allowed to accumulate to levels far exceeding normal may therefore be found to have lower pin temperatures than other units which, for example, have been freshly vented. Accordingly, in one preferred embodiment of this invention described below, baffles are provided to insure that noncondensable gases are forced from the pin and trapped in the space in the upper part of the boiler.

Referring now to Figures 3 and 4, a cylindrical block 15 is sealed to the upper part of the flat side of an elongated boiler 16 of semi-circular cross-section. Two tapered channels 17 and 18 are bored in the block such that the lower part 37 of lower channel 17 slopes downward approaching the boiler and the upper part 38 of upper channel 18 slopes upward towards the upper section of the boiler, and strip 39 forms part of the baffle.

arrangement, this strip being the section remaining in the block between the drilled channels or being an added, wedge-fitted or dove-tailed strip. Access into the boiler for the two channels is afforded by openings 19 and 20 in the side of the boiler, leaving strip 40, similar to strip 39, to form part of the baffle system. A hollow cylindrical draw pin 21 shown in Figure 4 is embedded in the side of the block near the end of the block. The hollow portion 22 of the draw pin has substantially the shape of a cone or truncated cone and is connected to the two channels in the block by opening 23 cut into the side of the block. Baffle 24 is affixed to the block between channels 17 and 18, being aligned with strip 39 divides opening 23 into an upper and lower channel 231 and 232, and extends into the hollow portion of the draw pin for a considerable distance, as shown in Figure 4. Baffle 24 can be conveniently wedge fitted between the end of strip 39 and the opposite edge 41 in block 15. The baffles can, if desired, be tapered, preferably paralleling the walls opposite them. As before, the draw pin is mounted at a downward slope of at least 3°, the taper of the hollow portion of the pin being at least 1° greater than the slope of the pin to allow drainage.

The boiler is divided into two sections by curved baffle 25 running the entire length of the boiler. One edge of the baffle is affixed to the flat side of the boiler between the openings 19 and 20, while the other edge of the baffle is attached at a point 26 near the bottom of the curved side of the boiler considerably below the liquid level of the heating fluid 27. Openings 28 in the baffle below the liquid level allow the liquid on each side of the baffle to attain a common level; as an alternative the openings 28 may be omitted if the lower edge of the baffle is not sealed to the lower part of the boiler wall, leaving a small gap at 26. The unit is also provided with vents 29, tubes 30 for heating elements 31, and a well 32 for a temperature controller attached at one end of the unit beneath the baffle.

In the preferred embodiment of the invention described above, noncondensable gases are forced into the upper section of the boiler where they are effectively trapped. Since the upper section of the boiler receives heat from the lower section only indirectly, condensation of vapor occurs in the upper section, causing a continuous gentle flow of vapor from the lower section of the boiler through channels 17 and 232, into the hollow pin, and through channels 231 and 18 into the upper section of the boiler. If desired, the velocity of flow through the unit may be increased by using less insulation over the upper part of the boiler than elsewhere on the unit, thus increasing the heat loss from the upper part of the boiler and promoting condensation of vapor. Since noncondensable gases are unable to mix with fresh condensable vapor and return to the pin, it is possible to allow them to accumulate for a long period of time before venting of the unit is required. In another embodiment of this invention the hollow pins are attached directly to a boiler of any desired shape. The dimensions of the pin, such as its length, are such to provide easy access to the pin by the operator and usually the insulation about the boiler insulates a small portion of the pin. The tapered section inside the pin and the mounting of the pin are fixed so that ready flow of liquid downward and of non-condensable gas upward is effected. If desired the pin and boiler may be equipped with baffles as in the preferred embodiment described above.

The apparatus of this invention is self-contained and occupies relatively little space. It is particularly adapted to be used with industrial draw-twisting and draw-winding equipment, e. g. of the type disclosed in U. S. Patent 2,474,912. The units are easily insulated and heat losses can be maintained at a very low level. The apparatus may be made long enough to supply pins for any desired

number of drawing positions. In industrial practice, banks containing at least twelve pins will usually be employed, while for ease of maintenance the unit will usually not contain more than about 30 or 40 pins.

5 Any departure from the above description which conforms to the present invention is intended to be included within the scope of the claims.

I claim:

- 10 1. Apparatus for drawing shaped articles at an elevated temperature comprising a sealed boiler containing a vaporizable liquid heating medium and having a plurality of lateral outlets above the liquid level of the heating medium; heating means adapted to heat the heating medium, the heat output of said heating means being regulatable; a temperature controller adapted to control the heat output from the heating means so as to control the temperature of the heating medium; and fitted to each of said lateral outlets in the boiler a draw pin sloping at an angle of at least 3° from horizontal, said pin having a hollow, concentric tapered portion in communication with the lateral outlet, the wide taper being at the end of the pin nearest the lateral outlet, the bottom taper sloping downward from horizontal towards the boiler at an angle of at least 1° and the upper taper sloping upward from horizontal towards the boiler.
- 20 2. Apparatus in accordance with claim 1 wherein said heating means comprises a plurality of electric heating elements with the heat output of at least one of said electric heating elements being regulatable and controlled by said temperature controller.
- 30 3. Apparatus in accordance with claim 1 in which said draw pins are cylindrical and have a diameter of 0.25 to 2.5 inches.
- 35 4. Apparatus in accordance with claim 1 in which said draw pins have an abrasion resistant ceramic surface.
5. Apparatus in accordance with claim 1 in which said draw pins contain a baffle dividing the space within said draw pins into upper and lower zones.
- 40 6. Apparatus for drawing shaped articles at an elevated temperature comprising a sealed boiler containing a vaporizable liquid heating medium and having a plurality of lateral outlets above the liquid level of the heating medium; heating means adapted to heat the heating medium, the heat output of said heating means being regulatable; a temperature controller adapted to control the heat output from the heating means so as to control the temperature of the heating medium; and fitted to each of said lateral outlets in the boiler a draw pin having a hollow, concentric, tapered portion in communication with the lateral outlet, the wide taper being at the end of the pin nearest the lateral outlet, the bottom taper sloping downward from horizontal towards the boiler to drain the condensate from the pin and the upper taper sloping upward from horizontal towards the boiler to remove noncondensables from the pin.
